UNITED STATES PATENT OFFICE.

JACOB S. JAMMER, OF NEW YORK, N. Y., ASSIGNOR TO WESTERN ELECTRIC COMPANY, INCORPORATED, OF NEW YORK, N. Y., A CORPORATION OF NEW YORK.

CARRIER-TRANSMISSION SYSTEM.

Application filed April 9, 1923. Serial No. 630,729.

This invention relates to carrier transmission systems, and more particularly to carrier telephone systems.

An object of the invention is to supply to a plurality of carrier current transmitting channels carrier oscillations of the same frequency from the same source without inter-channel modulation or cross-talk.

Another object is to prevent interchannel interference between transmitting channels of a carrier telephone system wherein a common source supplies to all channels carrier waves of the same frequency.

In accordance with this invention the transmitting channels of a plurality of single channel carrier systems supplied with carrier waves of the same frequency from a common source are connected to said source by frequency discriminating means tuned to the carrier frequency whereby the currents in one channel due to modulation are confined to said channel and therefore do not interfere with the operation of other channels.

The invention will be described as applied to a plurality of single channel carrier telephone systems, although it will be understood that it is also applicable to a plurality of multiplex carrier systems wherein one channel of each of the several systems is supplied with carrier waves of the same frequency from a common source.

While the invention is illustrated as applied to carrier transmission systems wherein the unmodulated carrier components are transmitted from the sending to the receiving terminals, together with the side bands representing signals it will be evident, of course, that it is also applicable to systems operating upon the principle of suppression of the unmodulated carrier frequency component.

In the drawing:

Fig. 1 illustrates diagrammatically only so much of a plurality of single channel carrier telephone systems as is necessary for an understanding of the invention.

Fig. 2 is a curve indicating the efficiency of the frequency discriminating means connecting the transmitting channels to the common carrier source.

The apparatus and circuits illustrated in Fig. 1 are located at the junctions between lines L_1 , L_2 , etc., over which low frequency

oscillations are to be transmitted and received and corresponding lines ML_1 , ML_2 , etc., over which modulated high frequency oscillations are to be transmitted and received.

While for the purpose of illustration only two sets of coupled low and high frequency lines are shown, it will be understood many more may be, and in practice usually will be, provided.

The illustrated sets of coupled low and high frequency lines and the coupling apparatus and circuits therefor are exactly alike so a description of one will suffice.

The low frequency line L_1 , according to the customary practice, may extend to and terminate at a telephone switchboard.

The high frequency line ML_1 extends to a distant junction (not shown) between such line and another low frequency line similar to L_1 , at which distant junction apparatus and circuits similar to those illustrated are provided.

The low and high frequency lines L_1 and ML_1 are connected by an outgoing high frequency transmitting channel TL_1 and an incoming high frequency receiving channel RL_1 .

The high frequency transmitting and receiving channels TL_1 and RL_1 are associated with the low frequency line L_1 through transformer 1.

The two channels TL_1 and RL_1 are rendered substantially conjugate by the provision of an artificial line or net AL_1 to balance the line L_1 .

The transmitting and receiving channels TL_1 and RL_1 , respectively, are connected to the high frequency line ML_1 through transmitting and receiving band filters TBF_1 and RBF_1 which separate the outgoing and incoming oscillations. Carrier oscillations of one frequency are employed for transmission in one direction and carrier oscillations of another frequency are employed for transmission in the opposite direction.

These band filters are of the general type disclosed in U. S. patents to George A. Campbell Nos. 1,227,113 and 1,227,114 dated May 22, 1917. The transmitting band filter TBF_1 is designed to pass currents of the transmitted carrier frequency and of frequencies within either the upper or lower

side band and to suppress currents of all other frequencies. The receiving band filter RBF_1 is designed to pass currents of the received carrier frequency and of frequencies within either the upper or lower side band and to suppress currents of all other frequencies.

The main line ML_1 may, of course, be utilized for the transmission of audio or lower frequency oscillations, high pass and low pass filters HPF_1 and LPF_1 being provided, as shown, to separate the audio and ultra audio frequency oscillations.

The transmitting channel TL_1 includes a modulator M_1 and the transmitting band filter TBF_1 , previously referred to, the output of the former being connected to the latter by a transformer 2.

The modulator M_1 may be of any well known type, but, as illustrated, is of the three element space current type.

Carrier oscillations of the frequency assigned for outgoing transmission are supplied to the modulator M_1 from a source CS common to all of the illustrated transmitting channels.

The low frequency modulating currents from the low frequency line L_1 delivered by the transformer 1 are impressed upon the input circuit of the modulator M_1 through a transformer 3.

The incoming or receiving channel RL_1 includes the receiving band filter RBF_1 , a demodulator DM_1 , and a low pass filter LPF .

The demodulator DM_1 may be of any well known type, but, as illustrated, is a three element relay of the space current type.

The amplitude of the received currents impressed upon the demodulator DM_1 is regulated by a potentiometer 4.

The low pass filter LPF which is of the general type disclosed in U. S. patents to George A. Campbell Nos. 1,227,113 and 1,227,114, is designed to pass only currents of the original modulating frequencies and to suppress currents of all other frequencies.

As previously stated, the source CS supplies to each modulator of the several illustrated transmitting channels carrier oscillations of the same frequency.

Since the input circuits of the several modulators are connected in multiple relation by the carrier supply leads 5, it becomes necessary to provide means to confine the modulating currents for a particular transmitting channel to such channel and thereby prevent interchannel modulation or cross-talk.

For such purpose, the carrier supply leads 5 are inductively coupled to each modulator input circuit by a transformer 6, the primary of which is tuned to the carrier frequency currents by an inductance 7 and condenser 8 cooperating with such primary, and the secondary of which forms, with variable

condenser 9, a loop circuit tuned to the carrier frequency.

This tuned inductive coupling is highly efficient for the transmission of currents of carrier frequency to which it is tuned, but is so inefficient for the transmission of currents of the modulating frequencies impressed upon the input circuit through transformer 3 as to prevent the passage of such modulating currents to the carrier supply leads 5.

Currents of both the carrier frequency and the modulating frequencies are present in the input circuit of the modulator M_1 and some modulation of the carrier currents occurs in the input circuit. Therefore there are also present in the input circuit currents of frequencies within both the upper and lower side bands of the carrier wave.

If such currents of frequencies within either the upper or lower side band are impressed upon the carrier supply leads 5, they will pass into the input circuits of the modulators of the other transmitting channels and thereby cause cross-talk between the channels.

To prevent such passage of these currents and thereby prevent cross-talk between the channels, the inductive couplings between the carrier supply leads and the modulator input circuits are tuned so sharply that they pass only currents of the carrier frequency.

Thus cross-talk and interchannel modulation between transmitting channels supplied with carrier currents of the same frequency from the same source are prevented.

Fig. 2 is an efficiency curve of the frequency discriminating circuits which couple the transmitting channels to the carrier current supply leads 5.

In this figure, frequencies are plotted against efficiency of transmission of currents of the frequencies represented.

Inspection of this efficiency curve shows clearly that the frequency discriminating circuits are highly efficient for the transmission of currents of carrier frequency and are very inefficient for the transmission of currents of all other frequencies.

The amplitude of the carrier currents supplied to the input circuits of the modulators is regulated by potentiometers 10.

The invention set forth herein is, of course, susceptible of various other embodiments and adaptations.

What is claimed is:

1. In a carrier transmission system, the combination of a plurality of modulators each included in a separate transmitting channel, a source of carrier currents from which carrier currents of the same frequency are supplied to each modulator, means to supply modulating currents of audio frequency to each modulator, and means comprising a circuit tuned to currents of carrier

frequency connected in the input circuit of each modulator and in circuit with said source.

2. In a carrier transmission system, the combination of a source of carrier oscillations, a plurality of transmitting channels each including a modulator, means to supply from said source carrier oscillations of the same frequency to the modulator of each channel, means to supply modulating currents of lower frequency to each modulator, and means comprising a circuit sharply tuned to currents of carrier frequency connected between said source and each modulator.

3. In a carrier transmission system, the combination of a plurality of modulators, each in a separate transmitting channel, a source of carrier currents from which carrier currents of the same frequency are supplied to each modulator, means to supply modulating voice frequency currents to each modulator, and means to connect said source to the input circuit of each modulator comprising a series circuit and a loop circuit inductively coupled and sharply tuned to currents of the carrier frequency.

4. A carrier transmission system comprising a plurality of transmitting channels, a source of carrier currents from which carrier currents of the same frequency are supplied to each channel, means associated with each channel to modulate in accordance with signals the carrier current supplied thereto, and means to prevent interchannel modulation comprising for each channel an inductive coupling between the source and said modulating means, said couplings being tuned to currents of the carrier frequency.

5. In a carrier transmission system, the combination of a plurality of modulators, each included in a separate transmitting channel, a source of carrier currents from which carrier currents of the same frequency are supplied to each modulator, means to supply to each modulator modulating currents of lower frequencies, and frequency discriminating means tuned to the carrier frequency coupling each modulator input circuit to said source.

6. The combination of a source of carrier current, a plurality of transmitting channels, each including a modulator to which carrier current of the same frequency is supplied from said source, means to supply to each modulator modulating currents of lower frequencies, and frequency discriminating circuits tuned to currents of the carrier frequency connecting the modulators to said source.

7. A plurality of transmitting circuits, a common source of oscillation of a single frequency for supplying signaling energy to each of said transmitting circuits, and means very sharply selective of oscillations of said single frequency connecting each of said circuits to said source.

8. The combination of a plurality of modulators each having an input circuit and each included in separate transmitting channels adapted for simultaneous and independent operation, separate sources of modulating currents connected to said input circuits, a source of carrier waves, a common supply circuit connecting said source of carrier waves to each of said modulator input circuits whereby carrier currents of the same frequency are supplied to each modulator, and a circuit tuned to currents of the carrier frequency connected between said common supply circuit and each of said modulator input circuits.

9. A plurality of transmission lines adapted for simultaneous and independent operation, a modulator associated with each of said lines, a source of carrier waves, a common supply circuit connecting said source of carrier waves to the input circuits of said modulators, whereby carrier currents of the same frequency are supplied to each modulator, means to supply modulating currents of audio frequency to the input of each modulator, and frequency discriminating means tuned to the carrier frequency connected between said common supply circuit and each of said modulator input circuits, whereby the modulating and modulated currents in each of said modulator input circuits are prevented from entering the other modulator input circuits.

10. In a carrier transmission system, the combination of a plurality of modulators each having an input circuit and each included in separate transmitting channels adapted for simultaneous and independent operation, separate low frequency lines connected to each of said modulator input circuits to supply currents of audio frequency thereto, a source of carrier currents, a common supply circuit connecting said source of carrier currents to each of said modulator input circuits, whereby carrier currents of the same frequency are supplied to each modulator, and means comprising a circuit tuned to currents of carrier frequency connected between said common supply circuit and each of said modulator input circuits.

In witness whereof, I hereunto subscribe my name this 2d day of April, A. D., 1923.

JACOB S. JAMMER.
